W. H. KING

MATCH HOLDING CIGARETTE CONTAINER

Filed April 1, 1922

UNITED STATES PATENT OFFICE.

WALTER H. KING, OF DENVER, COLORADO.

MATCH-HOLDING CIGARETTE CONTAINER.

Application filed April 1, 1922. Serial No. 548,592.

To all whom it may concern:

Be it known that I, WALTER H. KING, a citizen of the United States of America, residing at the city and county of Denver and State of Colorado, have invented a new and useful Match-Holding Cigarette Container, of which the following is a specification.

My invention relates to improvements in 10 match holding cigarette containers.

The object of the invention is to provide a container for either cigarettes or cigars, with means for holding a plurality of matches, said means being adapted to be 15 adhesively connected, thereby enabling the same to be attached to either boxes or packages.

Further to provide a cigarette box or package with a strip of suitable material 20 which is adhesively secured thereto, said strip being crimped or corrugated to provide a plurality of individual match holding pockets, and having a portion provided with a friction surface for convenience in 25 lighting the matches, whereby the necessity of carrying a box of matches in addition to the package, is eliminated.

These objects are accomplished by the device illustrated in the accompanying drawings in which:

Figure 1 is a perspective view of a cigarette holding box having a hinged cover, the inside surface of which is provided with the improved match holding attachment.

Fig. 2 is a perspective view of a similar box to that shown in Fig. 1, but having the match holding attachment secured upon the outside surface thereof.

Fig. 3 is a top view of a pocketed match holding attachment as it appears before being pasted upon the cigarette box or package.

Fig. 4 is a perspective view of an ordinary paper package or container for cigarettes showing the match holding attachment secured upon the outside surface of the same.

Figure 5 is a top view of Fig. 4.

Fig. 6 is a horizontal sectional view of a package, showing the match holding attachment secured to the inside surface of one of the sides thereof, and

Fig. 7 is a side view of a package having a match holding attachment secured to its outside surface and which is provided with a double row of match holding pockets, the pockets of one row being in end-to-end re-

lation with the pockets of the other row.

Referring to the accompanying drawings: The numeral 1 indicates a pasteboard box having a hinged cover 2. This box is a common style of box in which cigarettes are packed in small quantities, usually about twenty to the box, for the convenience of the individual smoker. Upon the inside face of the lid or cover 2 of this box is secured the improved match holding attachment, which is arranged and constructed as follows: The attachment comprises a strip of paper or other suitable material 3, which is pressed or folded to form a plurality of parallel corrugations or pockets 4, which are preferably closed at their bottom ends. The corrugations alternate with narrow flat portions 5, which are adapted to be gummed or given a coating of adhesive substance and each outside pocket terminates in a flat marginal portion 6 which is likewise adapted to be gummed so that when the attachment is applied to a box or package, it is adhesively connected thereto by means of the gummed flat portion 5, between each two pockets 4, and also by means of the marginal portions 6 which extend from the two outside pockets, thus providing a plurality of spaced individual match-holding pockets which are securely supported upon the box or package.

The strip 3 from which the match-holding attachment is formed is preferably wider than the length of the pockets, so as to extend beyond one end of the row of pockets, as shown at 7, to provide a surface upon which sand or emery 8, may be placed to afford a friction surface for convenience in lighting the matches; or this friction material if desired may be such as is used in lighting safety matches, so that either safety matches or matches of the common type may be supplied to the match holder.

In Fig. 1 the portion 7 having the friction element 8, extends above the open ends of the pockets, as the bottom ends of the pockets abut against one end of the lid or cover, but when the attachment is placed on the outside of a box or package, as in Figures 2, 4, and 7, the position of the friction element is immaterial.

In attaching the match holder to the inside face of a box lid, as in Fig. 1, the bottom ends of the pockets rest against one end of the lid so as to leave sufficient room between the open ends of the pockets and the

opposite end of the lid, to allow the matches to be withdrawn from the pockets, and small match sticks are preferably used so that when the lid or cover is closed down upon the box the matches will not exert undue pressure upon the cigarettes. In Figures 2, 4 and 5 the same character of match holder is used as in Fig. 1, but in Fig. 2 the match holder is attached to the outside of a box, 10 while in Figs. 4 and 5 it is attached to the outside of a paper package 1^a. In Fig. 6 the match holder is shown attached to the inside face of one of the sides of a paper package 1^b, in which arrangement the 15 matches are concealed, and as the matches take up very little room, the packages would not have to be enlarged in order to accommodate them.

In Fig. 7 is shown a side view of a package 1^c, having a match holder capable of carrying about twice the number of matches as are carried by the holders shown in the other views. In carrying out this arrangement, I provide a strip 9, having a double 25 row of corrugations or pockets 10, which are formed in end to end alinement, the outer ends of the pockets being open to receive the matches while their inner ends are closed and the strip 9 is provided with a friction 30 element 11, which for convenience extends parallel with the matches.

In practice, the strips from which the match holders are made are stamped or corrugated by any suitable means to provide a 35 plurality of parallel match-holding pockets alternating with narrow flat portions, the outside pockets being provided with flat marginal edge portions. The entire rear side of the strips, exclusive of the pockets, 40 is given a coating of adhesive material, and a portion of the front side of the strip is

supplied with a suitable friction element such as sand or emery, applied as in the case of match boxes in common use. The match holding attachments thus arranged, are 45 ready to be applied to boxes or packages of cigars or cigarettes of a size usually supplied to the retail trade, and the pockets are furnished with matches, thus providing each 50 purchaser of either a box or package of cigars or cigarettes, with a quantity of matches, and at a trivial cost to the manufacturer of the smoking material.

A small sized match would preferably be used so as to take up the smallest amount 55 of room, and also to permit a number of pockets equal to the number of cigars or cigarettes in the box or package upon which the attachment is pasted.

The attachment is cheap and practical, 60 and relieves the purchaser of a package of cigarettes, of the necessity of providing himself with matches.

Having described my invention, what I claim as new and desire to secure by Letters Patent is:

In a device of the character described, the combination with a box cover of a strip provided with a plurality of parallel match-receiving corrugations alternating with flat 70 portions and terminating in a flat end portion, said flat portions being adhesively secured to the inner face of said cover, said corrugations being substantially half the 75 length of the cover and said end portion having a sanded surface.

In testimony whereof I affix my signature in presence of two witnesses.

WALTER H. KING.
